UNITED STATES PATENT OFFICE.

PAUL M. HOTCHKIN, OF CHICAGO, ILLINOIS.

FOOTLIGHT.

Application filed June 22, 1925. Serial No. 38,771.

My present invention relates to foot-lights and has particular reference to a foot-light that may be caused to disappear and the pit or gutter in which the lights are installed may be covered.

The device is of compact construction and is especially adapted for use in show windows where foot light illumination is required under certain conditions and at other times the foot lighting may be dispensed with. In the latter instances it is of course desirable to close the pit and obscure the fixtures so that the floor of the show window presents no obstructions. The herein-described closed structure is capable of use also for stages for assembly rooms, lodge-halls and the like. The features of the invention reside in providing a device of the character mentioned that is made from a few simple parts that may be readily assembled and installed in the desired location, and after installation the structure will perform its functions in a dependable and effective manner.

On account of its simplicity the foot-light parts may be assembled by the manufacturer and sold to the trade and the user as a unit.

I prefer to carry out my invention in substantially the following manner, reference being made to the accompanying drawings that form a part of this specification.

In the drawings:—

Figure 1 is a transverse section of a portion of a show-window or stage showing the foot-lights installed and raised to the position for illumination.

Figure 2 is a similar view showing the structure in closed position.

Figure 3 is a fragmentary front elevation of the foot-light with portions broken away and in section.

The drawings show a typical or preferred embodiment of my invention and similar reference characters have been used to designate like parts wherever the same appear throughout the several views.

In said drawings, 5 designates the floor of the show-window or stage having an elongated pit or gutter 6 therein that may be closed by an elongated door 7, that is hinged along its longitudinal edge nearest the spectators, as shown at 8.

What may be termed the foot-light unit preferably comprises an elongated sheet metal conduit or channel 9 of slightly less

length than the pit 6 to hold the conductor wires is preferably of rectangular shape in cross-section as seen in Figs. 1 and 2, and one of its walls is provided with spaced openings in which electric sockets 10 are mounted. These sockets have radially disposed diverging arms 11 of spring metal the outer ends 12 of which are bent inwardly so that suitable reflectors 13 may be removably mounted therein to control the light rays from the bulbs A in the desired direction as will be understood.

The unit above described may be made of divers lengths so that a plurality may be employed to extend along the front of the stage, and the units are swingingly mounted in the pit and connected to the door in a manner so that, when the door is lowered and the pit is closed, the reflectors and light bulbs, as well as the other parts of the unit will be below the plane of the floor and covered by the door. The means for mounting the unit preferably comprises a plurality of angular brackets or V-shaped straps, one of the members 14 of each bracket being secured across one of the walls of the conductor channel or conduit 9 and the other members 15 of the brackets being extended to and pivotally connected to the hinge pieces 16 secured to the adjacent wall 17 of the pit. This wall, as seen in Figs. 1 and 2 is on the side of the pit opposite the hinge 8 of the door. Links 18 are pivotally connected at their lower ends to the angular brackets and at their opposite ends are similarly connected to hinge pieces 19 secured to the underside of the door 7.

With the before described structure, whenever the door is raised to an opened position (Fig. 1) the light-units will be raised to positions to direct the light rays onto the stage and the setting thereon or the show-window and its decorations, and upon the lowering of the door the links 18 swing the units downwardly upon the hinge pieces 16 so that the units are lowered into the pit and the floor is unobstructed. In order to support the units and door in desired positions when the latter is raised I provide one or more braces or struts 20 having pivotal connection with the door as at 21 and having slots 22 to receive wing-headed bolts that may be tightened onto the lugs that project from the wall 17, and the latter is slotted as at 24 to accommodate the strut 20 when the door is closed.

Other expedients may be employed in lieu of those specifically described herein and I desire it understood that such substitution and all obvious changes may be made without departing from the principles of my invention.

What I claim as new is:—

1. In a foot-light structure comprising a floor having an elongated pit therein and 10 a door closing said pit, a bracket hinged at one end to a wall of said pit, a link operatively connecting said bracket to said door, means for supporting an electric socket by said bracket within said pit, and 15 means for maintaining said door in divers opened positions.
2. A foot-light comprising a floor having an elongated pit therein, a door closing said pit, a plurality of brackets hinged to a wall 20 of said pit and extending transversely of the latter, links pivotally connected at their ends to said brackets and door, an elongated conduit within said pit and supported by said brackets, a plurality of electric sockets 25 in said conduit for the reception of light-bulbs, and means for maintaining said door in divers opened positions.
3. A foot-light comprising a floor having an elongated pit therein, a door hinged to 30 an edge of said pit for closing the same, a plurality of angular brackets pivotally connected to the wall of the pit opposite the door hinge and extending transversely of the pit, links pivotally carried by said door 35 and having connection with said brackets,

an elongated conduit supported by said brackets within said pit, a plurality of electric sockets mounted in said conduit, and struts connected to said door and having sliding adjustable connection with said locking members within said pit. 40

4. A light-unit for foot-lights comprising an elongated portable conduit, a plurality of electric sockets mounted in a wall of said conduit and supported thereby, reflector 45 holders, a plurality of substantially V-shaped mounting brackets secured transversely to said conduit one arm of which is adapted for pivotal attachment to a support, and operating links pivotally connected to said brackets intermediate the ends of the latter whereby to actuate the brackets and move the unit to divers positions. 50

5. The combination with a floor having a longitudinal pit therein and a door for closing said pit, of a light-unit consisting of a conduit, means for mounting a plurality of electric bulbs thereon, devices operatively connecting said unit and door, and members connecting said devices to a portion of the pit whereby the closing of said door lowers the light-unit into said pit and the opening of said door elevates said unit to a position to direct light rays laterally from said pit at intermediate angles between a vertical and 60 a horizontal plane. 65

Signed at Chicago, in the county of Cook, and State of Illinois, 1925.

PAUL M. HOTCHKIN.
